BUILDING CONSTRUCTION

Original Filed June 26, 1929

INVENTOR
WILLIAM H. ADAMS

BY *Marks & Clark*
ATTORNEY

UNITED STATES PATENT OFFICE

WILLIAM HUNTINGTON ADAMS, OF NORWALK, CONNECTICUT

BUILDING CONSTRUCTION

Application filed June 26, 1929, Serial No. 373,763. Renewed May 9, 1932.

This invention relates to building constructions, and particularly to walls, partitions, screens and the like, and has for its main object the provision of a wall, partition, or screen which can be easily and quickly assembled, and moreover, assembled in such a manner that it will stand normal usage without any defectiveness occurring therein.

More specifically the object of the invention is to provide an improved wall or the like made up of preformed section members adapted to be fitted together in interlocking engagement.

A still further object of the invention is the provision for a wall, screen or partition of sections of novel composite form adapted to be placed and locked together by means of cementitious material.

Further objects and features of the invention will be apparent from the following description taken in conjunction with the accompanying drawing and will be particularly pointed out in the appended claims.

In the accompanying drawing Fig. 1 is a front elevation of two sections forming a wall or partition according to this invention;

Fig. 2 is a sectional view along the lines II-II of Fig. 1 illustrating section members in appropriate juxtaposition.

Fig. 3 is an exploded view of the grooved edge of a section forming a feature of the invention.

Fig. 4 is a front elevation of a modification of my invention.

Fig. 5 is a view taken along the line V-V of Fig. 4.

Fig. 6 is a similar view to Fig. 5 showing a modified form, and Fig. 7 is a perspective view of a corner of one of the sections shown in Figs. 4-6.

In the drawing like references indicate like parts.

In carrying my invention into effect in one convenient manner, I form a wall, partition or screen of a number of section members one which may take the form of any composite structure, and in the particular case illustrated in Figs. 1 to 3 of the drawing, this takes the form of a cementitious member 1 comprising a metal reinforcement 2 covered

on either side by means of some cement, concrete which is preferably of cellular form, or the like 3 which itself may be covered on its outer side or sides by means of a further cementitious material such as a plaster 4. The reinforcement 2 may be of any suitable form such as a wire mesh, perforated sheet material preferably of undulating form, and in the present instance comprises sheet material preferably made of sheet metal of fluted form which in cross section is of zig-zag formation: this forms a key locking arrangement for the concrete or cement located on both sides thereof.

As shown in Fig. 2 each side of the section has a central tongue or abutting portion 5 which is preferably strengthened or reinforced in any suitable manner, and in the present instance is reinforced by a suitable formation of the main reinforcing member 2.

In the particular instance shown, the edge of the reinforcing member of sheet metal is cut at equal distance at right angles thereto and adjacent tags which are thus formed are bent alternately upwardly as at 6 and downwardly as at 7 so that adjacent tags are at an angle to one another. It will thus be seen that this formation of the ends of the metal reinforcement provides a strong reinforcement for the sides of the section members 1.

The edges of the section on each side of the abutment 5 are so shaped so that when placed in their correct disposition with respect to an adjacent section as shown in Fig. 2 a key joint will be formed. As shown in Fig. 2, a dove-tail arrangement is formed, but it will be obvious that the sides of the key joint, or in other words, the edges of the section members, may be curved instead of plane and may be suitably shaped in any other manner so long as when the sections are positioned with their tongues 5 abutting one another a key joint of some form will be produced.

When constructing a wall or partition by means of sections of the form indicated above, the sections are placed adjacent to one another with their tongues 5 touching, as illustrated in Fig. 2, and when so placed together, the intervening spaces are filled with some

cementitious material such as concrete which, when set, will obviously key the two sections together and will prevent any lateral displacement with respect to one another.

5 When it is desired to form inner facings of walls of houses and similar dwellings, I utilize a modification of my invention illustrated in one form in Figs. 4-7 in which is shown a slab or section which may be formed of a 10 block of any cementitious material such as a light cellular concrete backed by means of reinforcement preferably comprising a metal sheet of a form as previously described.

15 As shown in Figs. 5 and 6 the cement is indicated by 3 and the reinforcement comprising sheet metal is shown at 2. At the upper edges of the block the sheet metal is bent over the top edge and is then cut along lines at right angles to the edge so as to form 20 a set of tongues in the manner previously indicated in Fig. 3 and these are bent inwardly so as to project into the body of the concrete at varying angles as shown in section in Fig. 5, and in this manner the block is 25 reinforced on that particular part where it is most likely to be chipped or broken off. As will be seen from this figure, the upper edge of the block is shaped in such a manner 30 as to form with the corresponding block, a key or dove-tail which is filled in with a binder 9 when the blocks are placed in their correct positions, and in this manner the whole of the side of the room or building 35 may be covered effectively and in the simplest manner possible.

40 The wall framing usually takes the form of vertical and horizontal supports 11 and 12, and to these the slabs of reinforced material are attached in any suitable manner, as for example by nails 13—and when properly positioned and fixed the keying material 45 9 is forced in and allowed to set; the back of the blocks may be covered with a plaster or the like in known manner.

46 In a modification the sheet metal may be lapped over into part of the dove-tail formation and bent inwardly in the manner previously indicated in another part of the block, 50 this being more particularly shown in Fig. 6 where references 6 and 7 indicate the alternately bent tongues.

55 The side portions of the block are preferably formed in a similar manner as shown in perspective in Fig. 7 with the blocks adjacent thereto and so as to provide a dove-tail effect it will be thus possible to obtain by means of blocks of various sizes, a covering for the whole side of a wall as indicated in Fig. 4.

60 I do not wish to limit myself to the particular embodiments illustrated in the drawing for it is obvious that the section members may be curved or otherwise suitably shaped to suit requirements and while I have indicated

a light cellular concrete as being the preferred constituent material I wish it to be understood that any cementitious material may be utilized both for the blocks and the keying. The reinforcement of the projecting portions of the slabs may, for instance, be obtained by punching out the tags or by punching perforations along the edges of the sheet metal to secure a binding of the material to the sheet, these perforations being of any suitable shape. I may, for instance, cut out completely, alternate tags in the construction described above.

Such and similar modifications of the invention will be apparent to those skilled in the art, the invention being set out in the appended claims.

I claim:

1. A sectional block comprising a mass of cementitious material reinforced by sheet metal and having at least two of its edges formed with a projecting tongue adapted to form one half of a joint with a similar block the edges of said sheet metal being split and angularly disposed to reinforce said tongue. 85

2. A sectional block comprising a mass of cementitious material and a reinforcement of fluted metal sheet attached thereto said block having edges adapted to form one half of a key joint the adjacent edges of said sheet being cut into a plurality of tags, adjacent tags being angularly disposed and located within said edges. 95

3. A sectional block comprising a mass of cementitious material and a fluted metal sheet 100 embedded therein the edges of said block being shaped and adapted to form one half of a dove-tail joint the edges of said sheet within said block and adjacent the edges thereof being cut to form a plurality of tags to reinforce said edges of the block. 105

In testimony whereof I affix my signature hereto.

WILLIAM HUNTINGTON ADAMS.
